Inventor

FRANK SOLOMON

By his Attorney

Charles G. Gill

UNITED STATES PATENT OFFICE.

FRANK SOLOMON, OF NEW YORK, N. Y.

LINING FOR HATS.

Application filed September 19, 1922. Serial No. 589,071.

To all whom it may concern:

Be it known that I, FRANK SOLOMON, a citizen of the United States, and a resident of Bronx, in the county of Bronx, city and 5 State of New York, have invented certain new and useful Improvements in Linings for Hats, of which the following is a specification.

The object of the invention is to provide 10 a lining of improved character for hats, and more especially to provide a hat-lining in which the crown piece and its lining are connected together in a manner and by means which efficiently secure these parts 15 and maintain them in proper relation to each other and in addition improve the character and appearance of the hat lining as a whole. A further object of the invention is to provide a hat-lining whose parts are 20 properly secured together and which will correctly maintain its shape and position and at the same time present a soft appearance and be devoid of reeds, cords and the like which tend to kink or become irregular 25 under the conditions of use and mar the appearance of the interior of a hat employing them.

In accordance with the preferred embodiment of my invention the crown portion of 30 the lining is two-ply, consisting of an outer layer and an inner layer, or buckram lining for the outer layer, and these two parts are secured in face to face relation by stitching of zig-zag or overcast type adjacent to the 35 peripheral portions of the crown and independently of the skirt or apron member of the lining, and further in securing the two parts of the crown together I anchor on the face of the outer or exposed ply and adjacent to the peripheral portion thereof and 40 by means of the aforesaid stitching a line of body material which may be and preferably is of some pleasing color and of silk yarn or artificial silk yarn, this material in a 45 single strand being held nearly flat against the crown and at the same time being sufficiently exposed between the stitches to add to the appearance of the lining. The 50 stitches and said line of yarn or like material add body to the edge portions of the crown and improve both the structure and appearance of the crown and the lining as a whole. The said stitches extend back and forth on a zig-zag line over the top of the 55 line of yarn and thus hold said yarn pressed

down and protect the same from abrasion or displacement, while at the same time leaving the yarn exposed to view. I preferably employ an outer tinsel thread and an inner cotton thread in sewing the two plies of the 60 hat crown together and anchoring on said crown the line of yarn.

The apron member of the lining is secured to the edge portion of the crown by a line of stitching which is adjacent to but independent of the stitching by which the two 65 layers of the crown are secured together.

The invention will be fully understood from the detailed description hereinafter presented, reference being had to the accompanying drawings, in which:

Fig. 1 is a perspective view looking into a hat lining constructed in accordance with and embodying my invention;

Fig. 2 is a horizontal section, partly 75 broken away, through the two layers comprising the crown-member of the lining, said layers being shown juxtaposed ready to be secured together;

Fig. 3 is a corresponding view of the 80 same, illustrating the two layers or plies as secured together in accordance with my invention;

Fig. 4 is a transverse section through a portion of the hat lining, taken on the dotted line 4-4 of Fig. 1;

Fig. 5 is an elevation, on a larger scale, of a portion of the crown member of the lining and is presented to illustrate more clearly the stitching and the line of yarn I 90 apply to said portion; and

Figs. 6 to 9 inclusive illustrate a modified embodiment of my invention, Fig. 6 corresponding with Fig. 2 and showing the two layers for the crown member of the lining, 95 Fig. 7 illustrating these two layers as having been secured together by a line of ordinary stitching; Fig. 8 illustrating the application of my invention to the crown member of the lining, and Fig. 9 being a section corresponding with Fig. 4 but illustrating the modified embodiment of the invention.

In the drawings, 10 designates the crown portion of the hat lining and 11 the skirt or apron member thereof.

The crown portion 10 is formed of two layers 12, 13 which correspond in size and shape, the layer 12 being of suitable fabric to be exposed within the hat and the layer 13 being a coarser fabric and preferably 110

buckram and serving as a lining for the fabric 12.

Along the border portion of the crown 10 I secure the layers 12, 13 in face to face relation, as shown in Fig. 3 by a stitching composed of an outer zig-zag or overcast thread 14 and an inner zig-zag thread 15 in the same plane with the thread 14 and holding said thread 14 firmly to the layer 12 of the crown 10, as will be understood by reference to Figs. 3, 4 and 5. The thread 15 will preferably be of silk or cotton and the thread 14 is preferably of finer grade and of tinsel character. The stitches formed by the threads 14, 15 are usual and formed by a sewing machine of known type and this stitching firmly secures the layers or plies 12, 13 of the crown 10 together. In carrying out my invention, however, I apply to 20 the crown 10, against the layer 12 and while the stitching 14, 15 is being performed, a reasonably broad line of body material 16 and this line of material is, as shown in Fig. 5, secured against the face of the crown by 25 the thread 14 which zig-zags across said body material 16 and while firmly holding the same flat against the crown sufficiently exposes the material to render the same entirely visible. The body material 16 is soft 30 and preferably consists of a strand of silk yarn, the yarn known as artificial silk preferably being made use of by me.

I regard the body material or line of yarn 16 as an important addition to the crown 10 in that said line of material, plus the stitching holding it in place, serves to add body and stability to the peripheral portions of the crown and clearly defines the outline of the same so as to make the same presentable 40 for use within a hat. The line of yarn 16 will be of some pleasing color so as to add tone to the appearance of the lining, and I have found it convenient to incorporate two colors in the strand of yarn 16 so as to produce modifying effects in the appearance of the crown. The stitches 14, 15 not only secure the line of yarn 16 in place and sufficiently expose the same, but firmly secure the layer 12 and its buckram lining 13 together, the broadening out of the stitches 14, 15 adding to the security of the layer 12 and to the layer 13 and generally improving the structure and appearance of the lining as a whole. The zig-zag or overcast stitching 14 preserves the yarn 16 against abrasion or displacement, and when said stitches 14 are formed of tinsel they add materially to the style and general appearance of the lining.

After the crown 10 has been completed 60 I secure the same to the apron or skirt member 11 by a line of ordinary stitching 20, this line of stitching being exterior but in near relation to the stitching 14, 15, and line of yarn 16, as shown in Fig. 4. In hat linings employing a reed, cord or the like along

the edge of the crown, there is always an objectionable finish at the point where the two ends of the skirt or apron member 11 are joined to the crown of the lining, so that ordinarily a bow of ribbon or braid 70 is employed to conceal this joining. With my invention I am able to produce a finished border around the crown of the hat lining and do not require a bow or other concealing feature at the point in question. 75

In Figs. 6 to 9 inclusive I illustrate a modification of my invention or the manner of employing my invention, the modification consisting in permanently sewing the layers of the crown 10 together by an ordinary 80 line of stitching 21, as shown in Fig. 7, after which the stitching 14, 15 and line of yarn 16 are applied. Since this modification consisting of the line of stitching 21 is the only difference between the lining shown in Figs. 85 1 to 5 inclusive and that shown in Figs. 6 to 9 inclusive, I have numbered Figs. 6 to 9 correspondingly with the numbering of Figs. 1 to 5, so as to avoid needless repetition of description. The line of stitching 21 90 serves to secure the layers 12, 13 together, thereby making a firm and in effect one-piece body to receive the stitching 14, 15 and line of body material 16, and this may be 95 regarded by some as an advantage, but in my experience I have found no difficulty in omitting the line of sewing 21 and securing the layers 12, 13 together by applying the stitching 14, 15 and line of material or yarn 16 as a single operation, as I illustrate in 100 Fig. 4.

What I claim as my invention and desire to secure by Letters Patent, is:

1. A hat lining comprising a two-ply crown piece and an apron or skirt portion secured by sewing to a laterally extending edge portion of the crown piece, said edge portion and the adjacent edge portion of the apron or skirt being concealed back of the lining, and said crown piece having its two 105 layers fastened together and a line of soft body material secured thereupon by stitching composed of an outer zig-zag or overcast thread and an inner zig-zag thread, said 110 stitches crossing said line of body material and separated from one another to expose said material, and said stitches and line of material extending around said crown piece closely adjacent to said apron or skirt portion and being independent thereof. 115

2. A hat lining as claimed in claim 1, in which said body material is a layer of soft yarn, and in which the inner layer of the crown piece is of buckram. 120

3. A hat lining comprising a crown piece and an apron or skirt portion secured by sewing to a laterally extending edge portion of the crown piece, said edge portion and the adjacent edge portion of the apron or skirt being concealed back of the lining, and 125

said crown piece having along and against the face of its peripheral portion a line of soft body material and a line of stitches crossing said body material and binding the same against said crown piece, said stitches being separated from one another to expose said material, and said stitches and body

material being closely adjacent to said apron or skirt portion and being independent thereof.

Signed at New York city, in the county of New York, and State of New York, this 16th day of September, A. D. 1922.

FRANK SOLOMON.
